S. D. Quimby,

Traveling Bag,

No 14,900

Patented May 13, 1856.

UNITED STATES PATENT OFFICE.

SAMUEL D. QUIMBY, OF WINCHESTER, MASSACHUSETTS, ASSIGNOR TO EDWARD A. LOCKE.

FRAME FOR TRAVELING-BAGS AND MAIL-POUCHES.

Specification of Letters Patent No. 14,900, dated May 13, 1856.

To all whom it may concern:

Be it known that I, SAMUEL D. QUIMBY, of Winchester, in the county of Middlesex and State of Massachusetts, have invented 5 an Improvement in Mouth-Frames for Travelers' Bags, or other Articles of Like Description; and I do hereby declare that the same is fully described and represented in the following specification and the accompanying drawings, of which—

Figure 1, exhibits a top view of one of my improved mouth frames for a carpet bag or travelers' night sack, the said frame being represented as entirely open. Fig. 2 is a 15 side view of it exhibiting it as closed. Fig. 3 is an end view of it in a closed state. Fig. 4, is a transverse section of it. Fig. 5, shows an end view of a bag constructed with such a frame and represented as open.

20 The mouth frames of ordinary bags for travelers consist of two iron frames, or bent bars hinged together so that when they are opened apart, they form in appearance, one rectangular frame. From the manner in 25 which they are made and applied to the sack or bag, a difficulty often exists in opening them to an extent sufficient to introduce a large article into the mouth of the bag—the said mouth being more or less contracted 30 with reference to its entire width.

In carrying out my invention, I arrange 35 between each of the two folding side frames, what I term hinge extenders and gore closers, the lateral frames being hinged or jointed to said parts and arranged with reference to them in the manner I shall now proceed to describe.

In Figs. 1, 2, 3, and 4, A and B, are the 40 lateral frames or bent bars to which the bag is to be fastened at its mouth and to which the lock of the bar is generally fixed. These frames are hinged to opposite sides of two

triangular or approximately triangular gore closers and hinge extenders, plates or frames, C, D, arranged with reference to 45 the lateral frames, A, B, as shown in the drawings; the bag being also fastened to such gore pieces. The positions of the joints or hinges of the lateral frames and gore pieces are shown at, a, a, a, in the drawings. 50 The gore pieces may be made solid, or as open frames, in which latter case, they should be covered with leather or other suitable material made to extend entirely across them. They not only serve to extend the 55 hinges of the mouth frame apart from one another, but also to project into or close the opening between the frames, when they are brought together. And furthermore, they enable the bag to be opened to a greater extent, than it could be, were the lateral frames directly hinged together without such intermediate frames or gore pieces.

A traveler's bag constructed with one of my improved mouth frames will be found 65 much more convenient for either the reception of large articles or the removal of the same therefrom, than a bag made with a frame of the ordinary kind.

What I claim as my invention is the improved mouth frame or combination of two folding side frames, A, B, and two hinge extenders and gore closers C, D arranged, connected, and made to operate together substantially in manner and for the purpose, 75 as stated.

In testimony whereof I have hereunto set my signature this twenty eighth day of March A. D. 1856.

S. D. QUIMBY.
